UNITED STATES PATENT OFFICE

DENNIS L. HEALY, OF ST. PAUL, MINNESOTA

WALL HANGER FOR RADIATORS

Application filed April 1, 1926. Serial No. 99,012.

It is my object to provide an unusually simple and inexpensive hanger, adapted to facilitate the work of mounting radiators upon walls.

6 A further object of this invention is to provide a novel and efficient radiator hanger, adapted to permit a wide range of adjustment after a bolt for anchoring the device upon the wall has been secured in place.

11 Another object is to provide in a radiator wall support improved means for compensating for irregularities in a wall whereby a radiator may be secured in proper vertical position, irrespective of whether or not the abutting surface of the wall is smooth and vertical.

To this end, the invention consists in the novel arrangement and construction of parts hereinafter described, and particularly 20 pointed out in the claims.

Referring to the drawings, which illustrate the best form of my device at present known to me, Figure 1 is a side elevation of the hanger, mounted on a wall and showing a 25 radiator supported thereby in vertical section; Fig. 2 is a fragmentary, front elevation of a radiator supported upon the hanger; Fig. 3 is a side elevation of the hanger detached from the wall; Fig. 4 is a front elevation of the wall plate; Fig. 5 is a plan view of said plate; Fig. 6 is a horizontal section through the wall plate, showing the lower flange for holding the rod in upright position; Fig. 7 is a horizontal section taken on 30 the line 7—7 of Fig. 3 and showing the relative position of a radiator mounted on the hanger; Fig. 8 is a plan view of an alternate or equivalent form of wall plate; Fig. 9 is a plan view of the adjustable offset for maintaining the radiator in proper vertical position, the slot in the offset being of a shape which differs somewhat from the one shown in Fig. 7, and Fig. 10 is a front elevation or the offset.

45 As shown in the drawings, my device is adapted to be supported upon an anchor bolt 7, having a threaded end 8 projecting from the wall and adapted to receive a nut 9. The hanger has a wall plate 10, preferably made 50 of sheet metal, adapted to be placed broad-

side on the wall with the bolt 7 projecting through any one of the series of perforations 11 (Figs. 3 and 4). Projecting outward from the wall, at the upper edge of the plate 10, is a horizontal flange 12, formed with an 55 elongated slot 13, which extends parallel to the wall. A rod 14 is provided and is formed to be inserted in the slot 13 from above. This rod has a radiator supporting bracket 15 on its upper portion, adapted to extend between 60 two of the columns or tubes 16 of the radiator to support said radiator by engagement with one of the transverse portions 17.

A nut 18, threaded on the rod 14, is arranged to support said rod upon the flange 12. 65 To allow for a wide range of vertical adjustment of the rod 14, the central portion thereof has a long thread upon which the nut 18 may be turned upward or downward.

70 At its base, the plate 10 is formed with a second horizontal flange 19 having a slot 20 for the rod 14. This slot 20 permits movement of the rod 14 in vertical position and in a plane parallel to the wall. Teeth 20a are formed in the flange 19 along the margin of 75 the slot 20 nearest the wall and these teeth 20a are adapted to receive the rod 14 between them in pairs to hold said rod in upright position. Turning of the plate 10 upon the horizontal bolt 7 is prevented by a suitable 80 tooth or lug 21, adapted to be embedded in the wall beneath the bolt 7.

85 From the foregoing description, it will be understood that the radiator is pivotally suspended from its upper portion which rests in the bracket 15. To determine the angular position of the radiator relative to its pivotal axis, I provide an offset plate 22. This plate 22 is slidable upon the upper surface of the flange 19 and has an oblique slot 23 arranged 90 to receive the rod 14. The forward part 24 of the plate 22 projects so as to engage the rear faces or edges of the vertical members 16 of the radiator. Thus, the lower part of the 95 radiator is spaced from the wall the desired distance by sliding said plate longitudinally until it engages the rod 14 at the proper point along the forward margin of the oblique slot 23. Indentations 25 may be formed in the 100 front margin of the slot 23 for preventing 105

accidental displacement of the plate 22 after it has been adjusted to hold the radiator in proper upright position.

An upwardly bent, forward margin of the offset 22 is slotted to form a multiplicity of fingers 27 and a normally horizontal bolt 28 may be selectively inserted between any pair of these fingers. The bolt 28 is adapted to be inserted between the vertical members 16 of the radiator and is threaded to receive a nut 29 on its inner end. Disposed on the outer end of the bolt 28, is a head 30 of common type formed to engage the radiator members 30.

15 As shown in Fig. 9, the oblique slot 23 may be formed with wavy front and rear margins 23a. This wavy form of slot permits sliding the offset 22 while in continuous engagement with the rod 14, and at the same time insures against accidental displacement of the offset longitudinally whenever the radiator exerts pressure either toward or away from the wall. Thus, in operation the offset 22 may be held against movement irrespective 20 of whether or not the bolt 28 is used or is sufficiently tight to hold the radiator firmly against the part 24 of the offset 22.

To mount the common form of radiator with my device, it will be understood that two 30 or more of the hangers may be spaced horizontally one from the other on a wall. The anchor bolt 7 of each hanger is first secured in the wall at approximately the proper location for supporting the radiator. Now the plate 10 is mounted upon the bolt 7 by inserting the end of said bolt through one of the holes 11 and then turning the nut 8 on the projecting end of the bolt. When the nut 8 is tightened, the lug 21 will be embedded in the wall to maintain the flanges 12 and 19 approximately in horizontal position. The rod 14 is now inserted in the slots 13, 20 and 23 with the nut 18 above the flange 12. A pair of the teeth 20a engages the rod to hold it in substantially vertical position. The proper height at which the brackets 15 should support the radiator is now determined by applying a spirit level or by other suitable means, and said brackets are adjusted by turning the nuts 18 up or down on the threads as required. The radiator is next placed upon the brackets 15 of two or more of the hangers and the lower portion of the radiator is spaced from the wall by engagement with 50 the outer edges of the offsets 22.

The lower portion of the suspended radiator may easily be swung to proper position and the offset brought into engagement therewith by merely sliding it along the flange 19 until it projects the desired distance. Finally the radiator is secured against the offset by merely inserting the bolt 28 between pairs of the members 16 and fingers 27 with the nut 29 in place, and drawing the member 30 firmly against the radiator. A kerf in the head of

the bolt 28 facilitates turning said bolt while the nut 29 is held in the fingers 27. Thus, the offset 22 may be extended or retracted to constitute an abutment at the proper distance from the wall, irrespective of whether or not the wall plate 10 is in exact vertical position. The offset is used to compensate for irregularities in the portion of the wall abutting against the plate 10, and any desired adjustment may be obtained quickly and easily by merely sliding the plate 22 longitudinally upon the flange 19.

If, when it is attempted to place a radiator upon a bracket 15, it is found that the bracket does not register with an opening between vertical members 16 of the radiator, one or the other of the brackets, or both, may be moved by sliding the rods 14 in the slots 13 and 20. The teeth 20a permit the desired adjustment and maintain the rod 14 in substantially vertical position, because the rod is always pressed against or between the teeth under the weight of the radiator.

As shown in Fig. 8, the alternate or equivalent form of my device has a series of spaced perforations 26, instead of the elongated slots 13 in the upper flange 12, and these perforations 26 are duplicated by registering perforations in the lower flange 19. The rod 14 may be selectively inserted in any of the pairs of perforations 26 and fits loosely therein so as to facilitate adjustments when the bracket 15 is to be fitted between the members 16 in mounting a radiator. With such perforations, it is necessary to raise the rod 14 out of one perforation to permit insertion in another, whereas in the preferred form, the upper end of the rod 14 may be merely tilted towards the wall to free the lower end thereof from one pair of teeth 20a and permit engagement of said rod with another pair or while sliding the rod along within the slots 13 and 20.

Having described my invention what I claim as new and desire to protect by Letters Patent is:

1. In a support for a radiator, the combination with a wall piece having a projecting portion adapted to support a radiator, a normally upright rod extending upward from said projecting portion, a radiator seating bracket carried on the upper end of said rod, said bracket having a concave, upper surface and being adapted to carry the entire weight of the radiator and to suspend a radiator from a point above its center of gravity and a nut adjustably supporting said rod on said projecting portion.

2. In a support for a radiator, the combination with a bolt adapted to be secured in and to project from a wall, a plate perforated to receive said bolt and adapted to be secured thereto, a substantially horizontal flange projecting from said plate, a substantially vertical rod projecting above said flange and

adapted to be supported thereon, a second horizontal flange projecting from said plate beneath said first mentioned flange and engaging said rod to maintain the same in substantially vertical position and a radiator seating arm carried by the portion of said rod above said flange for engagement with a radiator between the vertical columns thereof, whereby said radiator may be supported entirely by suspending it from its upper portion.

3. In a support for a radiator, the combination with a radiator seating bracket adapted to suspend a radiator from a point above its center of gravity, a wall plate adapted to support said bracket upon a wall, and an offset for maintaining the lower portion of the radiator in spaced relation to the wall comprising a substantially horizontal plate arranged to engage the radiator with its forward portion and formed with an elongated slot extending obliquely relative to the wall and means in said slot for transmitting the thrust of said offset to said wall piece.

4. In a support for a radiator, the combination with a wall plate adapted to be secured to a wall, a substantially vertical rod adjustable vertically on said wall piece, a radiator seating bracket carried by said rod and an offset for maintaining the lower portion of the radiator in spaced relation to the wall comprising a substantially horizontal plate arranged to engage the radiator with its forward portion and formed with an elongated slot extending obliquely relative to the wall, said vertical rod being arranged to extend through said slot for transmitting the thrust of said offset to said wall piece.

5. In a support for a radiator, the combination with a wall piece adapted to be secured to the wall, a radiator seating bracket arranged to be supported on said wall piece, a substantially horizontal outwardly projecting member on said wall piece, an offset plate slideable on said projecting member and formed with an elongated, horizontal slot extending obliquely relative to the wall and means projecting from said member through said slot and permitting said offset plate to be extended and retracted for changing the position of the radiator with respect to a vertical plane.

6. In a support for a radiator the combination with a wall piece adapted to be secured to the wall, a radiator seating bracket arranged to be supported on said wall piece, an outwardly projecting member on said wall piece, an offset plate slideable substantially horizontally on said projecting member and formed with an elongated, substantially horizontal slot extending obliquely relative to the wall, means connecting said plate and member and projecting through said slot, said means permitting said offset plate to be extended and retracted for changing the posi-

tion of the radiator with respect to a vertical plane, and means for positively connecting said offset plate to the radiator.

7. In a support for a radiator, the combination with a wall piece adapted to be secured to the wall, a radiator seating bracket arranged to be supported on said wall piece, an outwardly projecting member on said wall piece, an offset plate slideable on said projecting member and formed with an elongated slot extending obliquely relative to the wall, means projecting from said member through said slot and permitting said offset plate to be extended and retracted for changing the position of the radiator with respect to a vertical plane, and a series of upwardly extending fingers on the forward edge of said offset plate arranged to be selectively fastened to the radiator.

8. In a support for a radiator, the combination with a wall piece adapted to be secured to a wall, said wall piece having a pair of spaced horizontal flanges and said flanges having perforations therein, a vertical radiator supporting element extending through said perforations in said flanges and said perforations permitting adjustment of said supporting element longitudinally thereof, and radiator abutment means engaging said element adjacent to one of said flanges and being adjustable to and from the wall.

9. In a support for a radiator, the combination with a wall piece adapted to be secured to a wall, said wall piece having a pair of spaced horizontal flanges, a vertical radiator supporting element adjustably associated with said flanges, and an adjustable abutment plate adapted to engage the radiator and provided with an oblique slot through which said element extends.

10. In a support for a radiator, the combination with a wall piece adapted to be secured to a wall, said wall piece having a pair of spaced horizontal flanges, a vertical radiator supporting element adjustably associated with said flanges, an adjustable abutment plate adapted to engage the radiator and provided with an oblique slot through which said element extends, and means for clamping said abutment plate to said radiator and serving to maintain said abutment plate in its newly adjusted position.

11. In a support for a radiator, the combination with a wall piece adapted to be secured to a wall, said wall piece having a pair of vertically spaced horizontal flanges, a vertical radiator supporting element adjustably associated with said flanges, an adjustable abutment plate having an oblique slot through which said element extends, one side of said slot being provided with a plurality of recesses for selective engagement with said element, and means for clamping said abutment plate to said radiator and serving to maintain any selected recess of the abutment

plate in engagement with said radiator supporting element.

12. In a support for a radiator, the combination of a rod extending upwardly, a radiator seating bracket carried on the upper end of said rod, said bracket being adapted to engage a radiator above its center of gravity, to suspend the same from a point above its center of gravity, a wall piece having a projecting portion perforated to receive said rod, a nut threaded on said rod for supporting the same on said projecting portion and means for securing said rod against swinging movement in a plane parallel to the wall while permitting adjustment of the radiator to and from the wall.

In testimony whereof, I have hereunto signed my name to this specification.

DENNIS L. HEALY.
